UNITED STATES PATENT OFFICE.

SIMPSON LUTES, OF PRIMROSE, KENTUCKY.

REVERSIBLE HILLSIDE TURNING PLOW.

1,406,569.

Specification of Letters Patent. Patented Feb. 14, 1922.

Application filed July 22, 1920. Serial No. 398,071.

To all whom it may concern:

Be it known that I, SIMPSON LUTES, a citizen of the United States, and a resident of Primrose, in the county of Lee and State 5 of Kentucky, have invented certain new and useful Improvements in Reversible Hillside Turning Plows, of which the following is a specification.

This invention relates to plows and more particularly to a hillside turning plow, and the primary object of the invention is comprehended in the provision of a plow of the class described, by which adjustment may be secured for the point, and between the 15 point and the moldboard, in order that the point may be adjusted to wear, being thereby adapted to be held in different positions so that only the extreme forward portion of the point will engage the ground and be subject 20 to wear, and may be maintained in line with the land bar or runner at all times, thereby producing an effective hillside turning plow, as well as insuring proper engagement with and turning of the earth, in addition to prolonging the life of the point.

A further object of the invention is to obviate the objections existent in the old types of plows in which the plow point at the portion thereof from the end of the frog 30 to the end of the point is arranged to contact with the ground and is therefore subject to wear, with the result that the bottom of the point wears all along, between the frog and the extreme end of the point, thus necessitating constant renewals of the points at considerable expense, and subjecting the other parts to unnecessary wear, as well as interfering with the plowing action, the present invention providing novel means 40 for adjustments of the point angularly up and down, so that the heel may be maintained out of contact with respect to the ground and lowered as the point wears, so that the point will last for a somewhat indefinite period.

A still further object of the invention is to permit adjustment of the point to insure proper plowing in combination with the land bar or runner and which permits the 50 point to be made with less concavity or with less abrupt bend from the frog than plows in which the points are not adjustable, so as to shed the soil better and not to take too much land in use, the point remaining 55 sharpened as well as the shears or side edges of the point.

Other and further objects of my invention will become readily apparent to persons skilled in the art, from a consideration of the following description when taken in conjunction with the accompanying drawings, 60 wherein:

Figure 1 is a side elevation of a hillside turning plow constructed in accordance with the invention,

Figure 2 is an opposite side elevation thereof,

Figure 3 is an enlarged central longitudinal sectional view through the plow point and moldboard, the handles, beam or stock 70 and standard being omitted.

Figure 4 is a rear elevation of the device as shown in Figure 3, for operating at either side,

Figure 5 is a sectional view taken on the 75 line 5—5 of Figure 3,

Figure 6 is an enlarged detail perspective view of the frog shield,

Figure 7 is a perspective view of one of the adjusting wedges or wedge plates,

Figure 8 is a perspective view of the base frog, and

Figure 9 is a fragmentary perspective view of one end of the land bar or runner.

Referring to the drawings in detail, there 85 is shown a hillside turning plow including a beam 10 having the handles 11 of the usual type connected to the rear end of the beam by braces 12. The plate 13 forms the stock and is connected fixedly to the beam 10 as 90 by bolts or rivets 14, the lower end of the plate connecting with or forming a part of the land bar or runner 15 pivoted for turning movement as indicated at 16, in the lower end and forward face of the standard 17, 95 which extends upwardly and forwardly and is secured as indicated at 18, to the moldboard 19 intermediately of the sides and near the rear end of the latter. The securing means may be in the form of a screw, 100 bolt or otherwise as is common in this art, and it is also to be understood that the beam, handles, braces and stock, as well as the standards, may be of any ordinary or well known construction in lieu of that above described and shown in the drawings.

The moldboard 19 is preferably tapered slightly toward its rear end and rounded, while the forward end thereof extending from the parallel sides is offset downwardly 110 as indicated at 20 and formed with a tapered forward end 21 extending to a point equi-

distantly from the sides and preferably having beveled side edges as shown. The forward end of the land bar or runner 15 is pivotally engaged as indicated at 22 in the 5 depending triangular extension 23 forming the base frog which projects at either side of the strip 24 forming a part thereof and near the forward end of which it is disposed. The frog extends in alinement with the land 10 bar 15 and in an inclined position above the same, the rear end of the strip 24 being bent upwardly when applied and connected to the moldboard 19 through the medium of a connecting bolt or the like 25 which also serves 15 for the connection of the apertured forward end of a brace 26 with the stock or shank 17, the latter being apertured horizontally for this purpose, preferably at right angles to the length thereof, in order to brace the 20 frog and moldboard in position, as well as the standard.

Arranged above the offset end portion 21 of the moldboard is the plow share or point 27, the same being of slightly concaved or 25 angular cross section, particularly at the apex or point thereof, said plow share or point proper being preferably of triangular formation. The sides adjacent to the point are also sharpened in order to provide shearing edges, as indicated at 28, to facilitate 30 cutting and plowing in sprouting ground, or in stubbles. A plurality, preferably a pair, of wedges, wedge plates or the like 29 and 30 of substantially triangular outline 35 with beveled edges and tapering in thickness toward their rear edges are disposed between the substantially flat intermediate portion of the point and the offset portion 21 so as to extend to the heel of the point at the 40 shoulder provided at said offset portion 20, and are detachably but firmly secured through the forward portion of the frog as through the medium of a bolt 31, the head thereof being embedded in the point 45 and the securing nut and washer being exposed at the bottom where it is readily accessible for renewal, adjustment or repair.

However, in order to protect the bolt and frog, a frog shield 32 is provided, the same 50 being preferably cast, while the base frog is preferably of malleable iron. The shield is tapered to a point, being substantially triangular and hollowed out at the top, the sides being beveled to conform to the edges 55 of the wedges, frog and cut sides of the plow share or point and having rearward extensions or furcations 32' extended rearwardly and made relatively thin, so as to engage 60 between the wedge plates or tapered forward end 21 of the moldboard and the projecting sides of the base frog in contact with the bottom face of said moldboard extension so as to straddle the frog 24 at either side, thus locking the parts in position firmly, in connection with a plurality, preferably a pair 65

of securing bolts 33 also extending through the intermediate portion of the plow share or point near the heel thereof, through the wedge plates, moldboard extension immediately forwardly of the offset portion or shoulder 20 and a brace or strip 34, which straddles the rearwardly extending portion of the base frog. By this means, the parts are securely held together, and the plow share or point, together with the moldboard, 70 may swing at either side of the stock, as indicated in Figure 4 of the drawings, when the device is in use, as indicated in Figures 1 and 2, for plowing on a hillside. Of course, the angle of disposition of the plow share or point will be automatically accommodated to the ground as the plow travels along, in order that the ground will be properly penetrated and cut, while permitting the reverse operation of the plow, that is, 75 permitting the use thereof when traveling in either direction. It should also be noted that the base frog, the wedge plate and the frog shield or guard, are apertured at the top faces for receiving the securing bolts, 80 in order to permit convenient assemblage or disassemblage of the parts, and in permitting the application or removal of the wedge plates, in order to adjust the plow point so that only the extreme forward portion or point thereof where angularly bent 85 relatively sharp, will be disposed in alinement with the frog extremity and the land bar or runner. In this way, the point will be prevented from wearing from one end 90 of the frog to one end of the point by reason of the fact that the rear portion or heel of the point will be maintained out of contact with the ground, and the angle need be very small, instead of the heel of the 95 plow being abruptly bent with respect to the forward portion thereof so that proper engagement with the ground surface may result. Thus, the renewal of the inside point is obviated and the angle of the disposition 100 of the point may be adjusted by regulating the thicknesses of the wedges, which latter may be added or removed so as to keep the end of the point in line with the land bar as 105 the point wears, so that a straight line connecting the land bar and point will strike the latter near the extreme end or apex 110 thereof. The point can be made with less abrupt bend from the frog and therefore will shed the dirt better, in addition to the 115 adjustment feature specified. The frog shield properly covers and protects the frog and securing means thereof so as to prevent contact thereof with the ground and interference with the plowing operation. 120

In order to disassemble the device, the two bolts are removed from the heel of the point, then the frog shield is slipped forwardly with the spaced portions thereof passing between the wedge plate and frog or 125

projections of the latter. The forward bolt may then be loosened, and by removing the point and corresponding wedge plates, angular adjustment of the point may be secured.

- 5 When a new point is inserted after the first one is worn out, the wedge plates are replaced as previously.

Having thus described my invention, what I claim is:—

- 10 1. A hillside turning plow comprising the combination with the beam, handles braced thereto, a stock, a land bar at the lower end of the stock and standard in which the rear end of the land bar is pivoted; of a moldboard attached to the upper end of the standard and having a tapered offset forward end, a frog secured to the moldboard and having a projection in which the forward end of the land bar is pivoted, a point 15 of relatively angular cross section having its forward portion substantially in alinement with the intermediate and rear portion disposed against the moldboard, displaceable rearwardly tapering wedges between the moldboard and point, a frog shield over the forward portion of the frog, securing means between the frog and point, and means connecting the guard with the point through the moldboard and wedge plates at the heel 20 of the point.

2. A hillside turning plow comprising a beam having handles braced thereto, a stock forming plate fixed to the beam and having a land bar at the lower end thereof, a moldboard having a downwardly offset forward tapered portion, a frog comprising a strip secured to the moldboard at the forward portion thereof and having a downward projection extending laterally at either side of the strip, said projection pivotally receiving the forward end of the land bar, a standard to which the rear end of the land bar is pivoted, said standard being connected to the moldboard whereby the latter is adapted to 40 swing to either side of the stock, and a relatively shallow point detachably secured to the frog and moldboard and having its forward bottom edge extended at a slight angle from the rear portion.

45 3. A hillside turning plow comprising a beam having handles braced thereto, a stock forming plate fixed to the beam and having a land bar at the lower end thereof, a moldboard having a downwardly offset forward tapered portion, a frog comprising a strip secured to the moldboard at the forward portion thereof and having a downward projection extending laterally at either side of the strip, said projection pivotally receiving the forward end of the land bar, a standard to which the rear end of the land bar is pivoted, said standard being connected to the moldboard whereby the latter is adapted to 55 swing to either side of the stock, a brace between the rear portion of the frog strip

and the standard, a frog shield over the forward portion of the frog strip, securing means carried by said frog strip and enveloped by said shield, said shield having spaced rearwardly projecting portions disposed between the moldboard and the frog projection, a point connected to said securing means and through the offset portion of the moldboard at the rearward extensions of the shield, and displaceable rearwardly 70 tapering triangular wedges disposed between the point and moldboard at the tapered forward portion of the latter.

4. The combination with a mold board and a stock having a land bar pivoted beneath the same; of a frog secured beneath the mold board to receive the forward end of the land bar, a substantially triangularly shaped point having the forward portion thereof provided with side cutting edges and a 80 forward portion directed upwardly at an acute angle relative to the horizontal and extended at an angle to the intermediate portion of the heel thereof, wedges disposed between the point and mold board, said 85 wedges being cut to a feather edge at the heel of the point, and securing means for the point passing through the wedge plates and mold board, said means also passing through the frog and permitting displacement of the plates.

5. The combination with a reversible plow stock and a land bar and a mold board connected thereto; of a point connected to the mold board at its heel portion, said point being of slightly concaved cross section especially emphasized at the apex thereof, and interposed means between the points and the mold board whereby the point may be adjusted angularly with respect to the ground 100 surface to vary the degree of inclination or slant thereof, said adjustment means being positioned in rear of the active portion of the point constituting the forward portion of the latter and spaced from the apex and rear end of the point and located near the extreme forward end of the mold board, and bracing means for the mold board.

6. In a hillside turning plow, the combination with a reversible moldboard having an offset forward portion tapered to a point and correspondingly tapered wedges feathered at their rear edges and fitting against the offset; of a frog having a strip connected to the moldboard, a point detachably connected to the frog against said wedges, said wedges being displaceable to adjust the inclination of the point, and a tapered shield member for the forward portion of the frog and securing means adjacent thereto.

7. The combination with a mold board and a stock; of a frog secured beneath the mold board, a substantially triangularly shaped point having the forward portion thereof provided with side cutting edges and 130

a forward portion directed upwardly at an acute angle relative to the horizontal and extended at an angle to the intermediate portion of the heel thereof, wedges disposed between the point and mold board, said wedges being cut to a feather edge at the heel of the point, and securing means for the point passing through the wedges and mold board, said means also passing through the frog and permitting displacement of the plates.

8. The combination with a mold board

and a stock; of a substantially triangularly shaped point having the forward portion thereof provided with side cutting edges and a forward portion directed upwardly at an acute angle relative to the horizontal and extended at an angle to the intermediate portion of the heel thereof, wedges disposed between the point and mold board, and securing means for the point passing through the wedges and mold board.

SIMPSON LUTES.
